UNITED STATES PATENT OFFICE

152,286

DESIGN FOR A BASE EXCHANGE WATER TREATMENT APPARATUS

Glenn A. Patterson, Delavan, Wis., assignor to
Sta-Rite Products, Incorporated, Delavan, Wis.,
a corporation of Wisconsin

Application June 26, 1946, Serial No. 131,032

Term of patent 14 years

(Cl. D16—2)

To all whom it may concern:

Be it known that I, Glenn A. Patterson, a citizen of the United States, residing at Delavan, in the county of Walworth and State of Wisconsin, have invented a new, original, and ornamental Design for a Base Exchange Water Treatment Apparatus, of which the following is a specification, reference being had to the accompanying drawing, forming part thereof.

In the drawings:

Figure 1 is a front elevational view of a base exchange water treatment apparatus, showing my new design;

Figure 2 is a side elevational view thereof;

Figure 3 is a top view thereof, and

Figure 4 is a rear elevational view.

Figure 5 is an enlarged top view of the control unit. The dominant features of my design reside

in the portions shown in full lines in the drawing.

I claim:

The ornamental design for a base exchange water treatment apparatus, substantially as shown and described.

GLENN A. PATTERSON.
